GIRDLE

Charles A. Hoffman, Wyomissing, Pa., assignor
to Vanity Fair Silk Mills, Reading, Pa., a cor-
poration of Pennsylvania

Application April 8, 1933. Serial No. 665,173

3 Claims. (Cl. 2—43)

This invention relates to girdles and proposes the construction of a garment of that type having an elastic form-fitting hip encompassing portion terminating in an elastic waist band at the top and having a full or gathered skirt of relative sheer material at the bottom. When worn, the skirt portion freely surrounds the legs in a zone just below the crotch.

One of the objects of the invention is to provide a garment in which diametrical portions of the skirt are detachably brought together to form a crotch closure, the flimsy material of the skirt being arranged so as to drape itself in a manner to close in on the areas displaced in the provision of the crotch closure, completely concealing the crotch closure.

Another object of the invention is the forming of skirt portion in sections united in the seam in the front and back, and utilizing areas symmetrical with the seams to constitute the crotch closure, whereby the seam reinforces the crotch closure, preventing stretching of the material.

Other objects of the invention will appear as the following description of a preferred and practical embodiment of my invention proceeds.

In the drawing which accompanies and forms a part of the following specification and throughout the several figures of which the same characters of reference have been employed to designate identical parts:

Figure 1 is a front elevation of a girdle embodying the features of the present invention, displayed on a figure;

Figure 2 is a perspective view displaying the crotch closure;

Figure 3 is a side view showing the skirt; and

Figure 4 is a front elevation showing the crotch closure released.

Referring now in detail to the several figures, the numeral 1 represents in general the girdle which comprises in its preferred form a relatively heavy knit elastic portion 2 adapted to encircle the lower portion of the body in the region of the abdomen, encompassing the hips. The upper edge of the elastic portion 2 terminates in an elastic waist band 3. On account of the fact that the elastic portion 2 is designed to be considerably stretched when worn, it acts to flatten the abdomen and to conform smoothly to the lines of the figure. The lower edge 4 of the elastic knit portion terminates substantially at the level of the crotch and attached to it in any suitable manner is the skirt 5 which is preferably of sheer material and made full or gathered. The skirt is bifurcated at the sides as indicated

by the reference character 6 to give freedom of movement to the legs.

The skirt is preferably formed of four sections, two at the front and two at the back and united in the middle of the front and back by seams 60 7 and 8. The material of the skirt is drawn in at the front and back in areas symmetrical with respect to the seams 7 and 8 forming crotch closure members 9 and 10, one of which is provided with a button 11 and the other with a 65 button loop 12. The edge of the skirt including those portions which constitute the crotch closure are suitably bound.

On account of the sheer nature of the skirt material and its fullness, those parts of the skirt 70 adjacent the areas drawn in to form the crotch closure, drape themselves into close adjacency as indicated at 13 and 14 in Fig. 3 so as completely to conceal the presence of the crotch members 9 and 10.

The seams 7 and 8 form median reinforcements 75 for the members 9 and 10 and prevent them becoming stretched. When the crotch members are unbuttoned, they naturally become part of the entity of the skirt from which they were derived, thus facilitating ironing.

The crotch portion may be worn either open or closed and when open it becomes an indistinguishable portion of the skirt.

While I have in the above description disclosed 85 what I believe to be a preferred and practical embodiment of the invention, it is to be understood that the specific details of construction as described are merely by way of example and not to be construed as limiting the scope of the invention as claimed.

What I claim is:

1. Girdle comprising a body portion and a skirt, the latter being made in sections united by seams in the middle of the front and back, 95 portions of said skirt symmetrical with said seams being drawn together between the legs forming a crotch closure, of which the seams constitute a reinforcement inhibiting stretching, and means for detachably connecting the ends 100 of said drawn-in portions.

2. Girdle comprising a body portion and a skirt, the latter being made in sections ununited at the sides and united by seams in the middle of the front and back, portions of said skirt symmetrical with said seams being drawn together between the legs forming a crotch closure of which the seams constitute a reinforcement inhibiting stretching, and means for detachably connecting the ends of said drawn-in portions. 110

3. Girdle comprising an elastic body portion adapted to encompass the hips, and a skirt of relatively sheer material adapted to surround the legs in a zone immediately below the crotch, said skirt being made in sections united by seams in the middle of the front and back, portions of said skirt symmetrical with said seams being drawn together between the legs forming a crotch closure of which said seams constitute

a reinforcement, inhibiting stretching, and means for detachably connecting the ends of said drawn-in portions, the sheer ness of said skirt causing the portions adjacent said drawn-in portions to drape themselves in close adjacency by gravity, concealing said drawn-in portions. 80
